UNITED STATES PATENT OFFICE.

CHARLES DOERING, OF CHICAGO, ILLINOIS.

DESIGN FOR A BEVERAGE-DISPENSING CABINET.

Application filed September 1, 1928. Serial No. 28019. Term of patent 7 years.

To all whom it may concern:

Be it known that I, CHARLES DOERING, a citizen of the United States, and a resident of Chicago, county of Cook, and State of Illinois, have invented a new, original, and ornamental Design for a Beverage-Dispensing Cabinet, of which the following is a specification, reference being had to the accompanying drawing, which is a perspective view of the beverage-dispensing cabinet showing my new design, forming a part hereof.

I claim:

The ornamental design for a beverage dispensing cabinet, as shown.

CHARLES DOERING.
